RAILWAY SIGNAL AND CONTROL SYSTEM

Ralph Linstra, Preakness, N. J., assignor of one-fourth to Orie and Jennie Sikkema, Preakness, N. J.

Application January 5, 1940, Serial No. 312,453

10 Claims. (Cl. 246—69)

This invention relates to block systems for railroads. The ultimate object is to provide for stopping any train when it comes into dangerous proximity to a preceding train; but whether or not such stopping is effected the object is also to signal the operator of the train under the condition indicated, and in the sense that some part must be moved from an inactive to an active position to effect the stopping such part itself amounts to a signal and may be so treated for the purposes hereof.

Generally stated, the improved system contemplates the following: At or near the adjoining ends of each two adjoining blocks is a stationary electric reversible motor. When any train attains any one of a number of points along the right of way spaced the same as these motors, as respectively adjoining them and each preferably at the outgoing end of a block, the train sets the motor relatively adjacent to such point in active state, setting the one next behind in inactive or back to normal state. The motor which is set active thereby energizes a contact preferably in the next preceding block and also another such contact in the next preceding block but one, one of these contacts being nearer one side and the other nearer the other side of the right of way. On each train are two other reversible motors adapted the one to be energized from any one of the left-hand contacts and the other from any one of the right-hand contacts. They are signaling media and in their normal positions maintain a "safe" (as green) signal; when one of these motors is caused, by a thereto-related energized contact, to move to the abnormal or active state it establishes a cautionary (as orange) signal and when the other is caused, by a thereto-related contact, to move to the active state it establishes a danger (as red) signal. Thus, the stationary motor having energized two contacts, one in one block and one in the next preceding block, the train which set that motor active is protected from a following train because, when the latter train enters the preceding block its one signal motor will set the cautionary signal and if and when it enters the other or second block its other signal motor will set the danger signal. Provision is had for returning each signal motor to normal position just prior to its reaching the point where the conditions may be such as to set it in active state.

In the drawings,

Fig. 1 is a front elevation of a stationary motor and shows diagrammatically parts of the circuits; 55 Fig. 2 is a diagram of several such motors and

stationary parts of the circuits with a leading train at X and a following train at X'.

Fig. 3 is a similar view of the signal motors on any train, with parts of the circuits shown diagrammatically and a certain cross-bar on the train and the shoes carried thereby in perspective; and

Fig. 4 is a fragmentary plan of the track and contacts 25—32.

The path of travel of the trains will be divided 10 into equal-length blocks, such as I, II, III and IV shown in Fig. 1, their direction of travel being as per the arrow in that figure.

At the outgoing end of each block is a stationary reversible rotary electric motor A, the armature shaft of which has a fixed gear 2 in mesh with the rack 3x of a lever 3 fulcrumed at 4 on the motor, a stand 5 having a dial 6 itself having two pairs of terminals 7a and 7b, they being all insulated as at 8. Pivoted on the stand and insulated therefrom as at 5a is a lever 9 adapted to be checked in its movements by stops 8a on insulation 8 and to engage either pair of terminals and which is a snap-switch, to wit, by having a suitably insulated spring 10 connecting a point above 20 the lever pivot with a point below the pivot. The upper end of lever 3 has a pin 3a loosely received in a slot 11 in lever 9. One pair of terminals is used for causing rotation of the motor in one direction and the other for causing such rotation 30 in the opposite direction, as will appear. When the rotation starts in either direction the lever 3 at first idles, due to the slot in lever 9, but ultimately shifts that lever until, by its spring, the latter assumes its other circuit-closing limit. On 35 and insulated as at 12 from the motor casing is a pair of terminals 13. A blade forming a circuit-closer 14 projects radially from the armature shaft and when it turns in one direction it engages both terminals, clearing them when it turns 40 in the opposite direction. The described switch 9 determines that the armature shall complete less than a full rotation.

In the cab of the locomotive or driver of each train is a pair of motors B—B' in all respects the 45 same as the motor A except that they lack the parts 13—14, that is to say, each has the gear 15, lever 16, stand 17, dial 18, insulated pairs of terminals 19a—19b and snap-switch 20 movable by 50 the lever. In the cab also are these signals, green or safe, G, orange or cautionary, O, and red or danger, R, all being electric lamps.

A circuit, now to be described and shown by light solid lines, is in part on each train and in 55

part stationary, with the energy source also on the train.

From ground 21 on the driver extends a conductor 22 including an energy source 23 having 5 a terminal shoe 24 to wipe a (suitably insulated) contact 25 at the outgoing end of each block between the tracks T. A stationary conductor 26 leads from contact 25 to the motor A and is then grounded at 26x, the same having a break therein 10 formed by the terminals 7a. Another conductor 27 leads from a conductor 31 (to be referred to) to the next preceding motor A and is then grounded, as at 26x, the same having a break therein formed by the terminals 7b. On shoe 24 15 of any train engaging a contact 25 it causes rotation of the adjoining motor A forward or clockwise, to shift switch 14 thereof to close a circuit (to be described) having a break therein at terminals 13, and rotation of the next preceding motor A reversely or counter-clockwise, to shift its switch to open said circuit at the corresponding terminals 13. (I term the conductors 26 forward-driving and the conductors 27 reverse-driving.) It will be understood that when 20 said contact 25 was thus engaged by shoe 24 the break for said adjoining motor stood closed by the snap-switch and that it remains closed until the clockwise rotation of that motor has closed the break at 13 and shifted the snap-switch so as 25 to open break 7a and close break 7b to energize the next preceding motor.

The motors A are circuit-closing media, (i. e., each for closing the corresponding break at 13) and when the train passes out of a block it establishes the medium in that block in active or circuit-closing state, to wit, at 13, and the medium in the next preceding block in inactive or circuit-breaking state.

The signal-controlling circuit controlled by 40 any motor A is as follows, being, as will appear, also in part stationary and in part on each train and shown by heavy solid lines:

A main line 29 extends from ground along the track T and contains an energy source 30. From 45 it extend leads 31 the same in number as the blocks and each having a break formed by the terminals 13 on the adjoining motor A and two branches 31a-31b, branch 31a leading to a contact 32 adjoining the next preceding motor A but 50 one and branch 31b leading to a contact 33 adjoining such next preceding motor A. (The contacts are of course suitably insulated and, like the motors A, they are at the outgoing ends of the blocks to which they respectively correspond.) Contacts 32 and 33 are respectively adjacent the left and right sides of the track and each is set somewhat after contact 25. Thus, when a train by its shoe 24 engaging a contact 25, has closed the described circuit for driving 55 the motors A the adjoining motor A will effect energizing of the two contacts 32-33 controlled thereby, wherefore contact 32 will as will appear be effective to set the O signal and contact 33 to set the R signal on the train following. So 60 much for the stationary part of the (signal-controlling) circuit now being described. The part thereof on each train is as follows: 34 and 35 are two shoes on each train respectively arranged to wipe the contacts 32-33. They form the terminals of conductors 36-37 which respectively supply current to the motors B-B' to rotate 65 them from their normal positions shown, or respectively clockwise and counter-clockwise, being both grounded at 36a. That is, when a following train leaves a block (as III) in which by a pre-

ceding train the contact 32 has been left energized the motor B of such following train will be driven clockwise and if and when the train then leaves the next block (as II) its motor B' will be driven counter-clockwise. It remains here to 5 consider how the motors B-B' are reversed: Flanking shoe 25 are contacts 38-39 forming the terminals of conductors 40-41 which serve as extensions on the train of conductor 22, being respectively connected to motors B-B' to drive 10 them reversely. The shoe 25 is placed somewhat in advance of the adjoining contact 32 or 33. When the train passes any contact 25, therefore, current flows from the source 23 on the train to shoe 25, thence via contacts 38-39 and conductors 40-41 to the motors and so is potent, if either of the motors has been driven from its shown or normal position, to reverse it; and, this always occurs before a contact 34 or 35 attains its contact 32-33 either of which, if it stands 20 energized by the preceding train, is to drive the corresponding motor from normal position.

The signal circuit connections are as follows: A lead 42 contains signal G and the terminals 19a of both motors B-B' and is grounded; a lead 43 contains signal O and terminals 19b of motor B and is grounded; and a lead 44 contains the signal R and the terminals 19b of motor B' and is grounded. All the leads extend from conductor 22. 30

The shoes 24-34-35-38-39 may all be affixed to a cross-bar C on the driver of each train.

To recapitulate the operation, and first as to a leading train, as X, assumed of course to be on the track, Fig. 2: This train is assumed to have 35 just left block II and so passed contact 25 therein. The energy source 23 thereon has therefore acted, by engagement of shoe 24 with said contact, to energize the motor A adjoining said contact which thereupon assumed the position shown and so closed the conductor 27 at 1b so that the preceding motor A is reversed or returned to its normal position. (The power for 40 (i. e., reversely) driving the latter motor A—since such motor is remote from the other motor—is desirably obtained from the stationary source 30.) Further, the contacts 32-33 appertaining to the first motor are energized from source 30 so that the conditions potentially exist for successively setting the O and R signals on a 45 following train departing first from block III and then from block II.

The following train passes the contact 32 in block III (it being assumed that the leading train has not meanwhile in block I reversed the motor 55 A in block II) so that its motor B is made to cause its switch 20 to disestablish the G signal and set the O signal; if it continues and passes the contact 33 in block II its motor B' will cause the switch 20 to set the R signal.

But in any event just before a signal is set on the following train by its passing contact 32 or 33 the corresponding motor B or B' is inevitably restored to its normal or shown position by the energy from the source 23 on the train, 65 thus restoring the G signal, to wit, because contact 25 is ahead of contacts 32-33 and is wiped both by shoe 24 (which controls two motors A) and contacts 38-39 for effecting reversal of motors B-B' before either of such contacts is energized from 32-33. 70

Otherwise stated, the motors A derive their forward-driving energy from the source 23 on the train, the normal position of each being when 7a stands closed; they derive their reverse-driv- 75

ing energy (each when the next motor to the right is driven forwardly and so closes 1b) from the fixed source 30. When any motor A is driven to abnormal position (second from the right in Fig. 2), besides thus reversing the next preceding motor, it energizes, for the protection of the following train, a contact 33 at the right side of the track and (here) in the next preceding block and a contact 32 at the left of the track and in 10 the next preceding block but one. The energy for that purpose is derived from the fixed source 30. That being done, the following train on encountering 32 will have its motor B driven forwardly (from fixed source 30) so as to set the 15 O signal and if it continues and contacts 33 it will have its motor B' driven forwardly to set its R signal. In this connection it is noted that the following train might, with its cautioning or O signal proceed into the next block and have its 20 red or R signal also set. To avoid this, or always to reverse both motors B—B' to the green or G position just before they might receive energy from 32 or 33, they are subjected to a reversing impulse which will reverse them if of course they 25 are not already reversed or in normal positions.

As for the actual stopping of the train (to wit, by cutting off the power or applying the brakes, or both), either motor B or B' may be treated as a source of power for that purpose.

30 Any suitable means for transmitting such power may of course be used.

By way of analysis of my invention and in elucidation of the appended claims I remark as follows:

35 The invention contemplates that each of the electromotive devices A may be regarded as of itself in effect a signaling medium, for instance, as assuming the "on" position when it is driven forwardly and the "off" position when it is driven 40 reversely. According to my invention each such device is driven to the "on" position from a source on the train and any means, controlled by said device, for reversing a device thereto preceding is broadly within the invention.

45 Again, in respect to the provision for signaling existing on a train itself, while it is preferable to include two signaling media, as B—B', such is not indispensable. Preferably, of course, the driving of any one such medium is to be controlled by a leading train, though such is not indispensable.

Again, given leads (as 31) corresponding in number to the blocks and respectively having contacts (as 32) in the respective blocks and 55 other contacts (as 33) in the respective preceding blocks with the two series of contacts offset from each other transversely of the track, so long as there are independent conductors on the train respectively having terminal shoes arranged to 60 engage in succession the contacts of the respective series, thus to form of a lead and a conductor a circuit on each such engagement, it is not material what character the electromotive means (thus receiving independent impulses 65 from the two conductors) may assume, or whether or not each lead is of the closable type and, if so, how it is closed.

Having thus fully described my invention, what I claim is:

70 1. In combination, a track, a train arranged to travel along the track, a portion of an electric circuit on the train including an energy source and having a terminal shoe, a series of reversible electromotive devices arranged at intervals along 75 the track, forward-driving conductors for the re-

spective devices respectively having breaks therein and contacts arranged at substantially the same intervals as said devices and to be engaged successively by said shoe, each device normally closing the corresponding break but when moved adapted to open the same and each device and its conductor, on engagement of the corresponding contact by said shoe, forming the remainder of said circuit, and means, controlled by the device which is at any time driven forwardly, for reversing a device thereto preceding. 5

2. In combination, a track, a train arranged to travel along the track, a portion of an electric circuit on the train including an energy source and having a terminal shoe, a series of reversible 15 electromotive devices arranged at intervals along the track, forward-driving conductors for the respective devices respectively having breaks therein and contacts arranged at substantially the same intervals as said devices and to be engaged successively by said shoe, each device normally closing the corresponding break but when moved adapted to open the same and each device and its conductor, on engagement of the corresponding contact by said shoe, forming the remainder 20 of said circuit, and a normally open electric-circuit-forming means, arranged to be closed by the device which is at any time driven forwardly, for reversing a device thereto preceding. 25

3. The combination set forth in claim 2 characterized by the last-named means having a fixedly located energy source. 30

4. In combination, a track, a train arranged to travel along the track, an electromotive device to be driven arranged on the train, a portion 35 of an electric circuit on the train including said device and having a terminal shoe, normally open leads respectively having contacts arranged at intervals along the track and to be engaged successively by said shoe, said portion and a lead, on engagement of the shoe with the contact of such lead, together forming an electric circuit, means providing an energy source for each circuit when formed, and means to close such lead independently of all the others. 40

5. In combination, a track, leading and following trains arranged to travel along the track, an electromotive device to be driven arranged on the following train, an open electric circuit system having a part stationary and formed with a break, 50 and a part on the following train, the latter part including said device and being adapted to engage the first-named part to form therewith said circuit system, a stationary electromotive device to close said break, and a circuit including the latter device and having a portion stationary and a portion on the leading train, the latter portion being adapted to engage the first-named portion and thereby establish said circuit in closed state to drive the second-named device. 55

6. In combination, a track, leading and following trains arranged to travel along the track, an electromotive device to be driven arranged on the following train, a portion of an electric circuit on the following train including said device and having a terminal shoe, a stationary conductor means including normally open leads respectively having contacts arranged at intervals along the track and to be engaged by said shoe, said portion and means, on engagement of the shoe with any 70 contact, together forming such circuit, stationary electromotive devices drivable to close the respective leads in succession and arranged along the track, an electric circuit, having a part thereof arranged on the leading train and parts in- 75

cluding the respective latter devices and arranged along the track and to be independently engaged by said first-named part whereby to complete the latter circuit, for driving the latter devices in succession, and means providing energy to the circuits.

7. In combination, a track divided into blocks, a train arranged to travel along the track, electromotive means to be driven arranged on the train, normally open leads relatively adjacent and corresponding in number to the respective blocks and each having a contact in the adjacent block and another contact in the next preceding block, the contacts which are adjacent the respective blocks forming a series offset transversely of the track from the other series of contacts, two independent conductors on the train for driving and connected with said means and respectively having terminal shoes arranged to engage in succession the contacts of the respective series, any conductor on engagement of its shoe with a contact forming with the corresponding lead an electric circuit, means to close the leads, such lead independently of the other leads, and means providing an energy source for each such circuit when formed.

8. In combination, a track, leading and following trains arranged to travel along the track, electromotive means to be driven arranged on the train, normally open leads relatively adjacent and corresponding in number to the respective blocks and each having a contact in the adjacent block and another contact in the next preceding block, the contacts which are adjacent the respective blocks forming a series offset trans-

versely of the track from the other series of contacts, two independent conductors on the train for driving and connected with said means and respectively having terminal shoes arranged to engage in succession and contacts of the respective series, any conductor on engagement of its shoe with a contact forming with the corresponding lead an electric circuit, means, controlled by the leading train, to close the leads successively, and means providing an energy source for each such circuit when formed.

9. In combination, a track, a train arranged to travel along the track, a reversible electric motor on the train, forward-driving and reverse-driving conductors for the motor, leads arranged at intervals along the track to be successively engaged by one conductor and on such engagement forming therewith an electric circuit, means, arranged along the track, to form an electric circuit with the other conductor following each and before the next such engagement, and means providing energy to the two circuits.

10. In combination, a track, a train arranged to travel along the track, a reversible electric motor on the train, forward-driving and reverse-driving conductors for the motor, leads arranged at intervals along the track to be successively engaged by one conductor and on such engagement forming therewith an electric circuit, means, arranged along the track, to form an electric circuit with the other conductor following each and before the next such engagement, and separate means, one on the train and the other stationary, providing energy to the respective circuits.

RALPH LINSTRA. 35
